CLAIM

The ornamental design for a first aid kit bag, as shown and described.

DESCRIPTION

FIG. 1 is a perspective view of a bag for a first aid kit, the bag in a loading position;

FIG. 2 is a front elevation view;

FIG. 3 is a rear elevation view;

FIG. 4 is a left side elevation view;

FIG. 5 is a right side elevation view;

FIG. 6 is a plan view;

FIG. 7 is a bottom plan view;

FIG. 8 is an environmental view of the bag showing contents outside the bag; and,

FIG. 9 is a perspective view of the bag with the contents inside the bag and the bag in a sealed position.

The broken lines of FIG. 7 show portions of the first aid kit bag that form no part of the claimed design. The broken lines of FIG. 8 showing contents outside the bag represent environment of the article that forms no part of the claimed design. The remainder of the broken lines show stitching that does not form part of the claimed design.

1 Claim, 8 Drawing Sheets
